PICNIC TABLE

Frank W. Beller, Aurora, Ill., assignor to Belson Manufacturing Co. Inc., North Aurora, Ill.

Filed Mar. 12, 1973, Ser. No. 340,203

Term of patent 14 years

Int. Cl. D6—03

U.S. Cl. D6—27

FIG.1

FIG.2

FIG.3

FIG. 1 is a front perspective view of a picnic table showing my new design;

FIG. 2 is an end view of the table wherein a portion of the leg has been omitted for convenience of illustration;

FIG. 3 is a side view thereof; and

FIG. 4 is a bottom view of the picnic table.

I claim:

The ornamental design for a picnic table, as shown
